UNITED STATES PATENT OFFICE.

HARRY A. HANNUM, OF SPRINGFIELD, MASSACHUSETTS, ASSIGNOR TO WINCHESTER REPEATING ARMS CO., OF NEW HAVEN, CONNECTICUT, A CORPORATION.

ROLLER-SKATE WHEEL.

1,347,777.

Specification of Letters Patent. Patented July 27, 1920.

Application filed March 17, 1920. Serial No. 366,479.

To all whom it may concern:

Be it known that I, HARRY A. HANNUM, a citizen of the United States, residing at Springfield, in the county of Hampden and 5 State of Massachusetts, have invented a new and useful Improvement in Roller-Skate Wheels; and I do hereby declare the following, when taken in connection with the accompanying drawings and the characters of 10 reference marked thereon, to be a full, clear, and exact description of the same, and which said drawings constitute part of this application, and represent, in—

Fig. 1, a view in side elevation of my 15 improved roller-skate wheel.

Fig. 2, a view thereof in transverse section.

Fig. 3, a broken sectional detail view 20 showing the tread forming an integral part of the exterior side-plate, before the positioning-shoulder is formed thereupon.

Fig. 4, a corresponding view after the formation of the positioning-shoulder.

Fig. 5, a similar view showing the edge of 25 the interior side-plate in place against the said shoulder with the edge of the same spun over it for its retention in place.

My invention relates to an improvement 30 in ball bearing roller-skate wheels of the so-called inclosed type, the object being to produce at a low cost for manufacture, a skate-wheel of improved appearance and constructed with particular reference to being easily assembled so as to be free from the 35 wobbling of the wheel on its hub.

With these ends in view, my invention consists in a ball-bearing skate wheel of the inclosed type, the said wheel having certain details of construction as will be hereinafter 40 described and pointed out in the claims.

In carrying out my invention, as herein shown, I employ a struck-up, circular, exterior side-plate 2 formed with an integral tread 3, the outer edge of which is reduced 45 in thickness to produce upon its inner face a positioning-shoulder 4 providing a bearing for the inner face of the outer edge of a circular, interior side-plate 5 which is held in place by having the extreme edge of the 50 tread 3 spun over it to form the retaining-flange 6, whereby the two plates are firmly secured together.

Before the two plates 2 and 3 are assembled, as described, the wheel-hub 7 is inserted between them, this hub having a 55 peripheral race-way 8 for the balls 9 which are also confined by ball-cups 10 produced by striking up the inner portions of the plates, as clearly shown in Fig. 2. The said plates are so proportioned, however, that 60 when the edge of the inner plate is brought to a bearing upon the shoulder 4 of the exterior plate, the opposed high points 11 and 12 of the respective plates are held apart to form a compensating-space 13 which permits the forcible closing-in of the ball-cups 10 to the extent required to prevent the wheel proper from wobbling on the hub. This latter is an important feature of my 65 improvement, since it enables every wheel 70 to be absolutely corrected after assemblance, in case any wobbling then manifests itself, due to slight inaccuracies in construction or variations in the thickness of the stock.

I claim:

1. A ball-bearing roller-skate wheel of the inclosed type, the said wheel consisting in a hub, and two plates inwardly struck up to form ball-cups and secured together in spaced relation, whereby their oppositely 80 located high points are kept out of contact to provide for correction after assemblance, for the prevention of wobbling.

2. A ball-bearing roller-skate wheel comprising a hub having a race-way, a struck-up exterior side-plate formed with a tread furnished with a positioning-shoulder, and an interior side-plate, the edge of which is abutted against the said shoulder and which is held in place by the spinning over it of the 90 edge of the said tread, and the ball-cup portions of the said plates being held apart by the said shoulder to form a compensation-space to provide for correction after assemblance, for the prevention of wobbling. 95

In testimony whereof, I have signed this specification in the presence of two subscribing witnesses.

HARRY A. HANNUM.
